H. P. DICKERSON.
HEEL REMOVING DEVICE.
APPLICATION FILED MAY 26, 1920.

1,371,474.

Patented Mar. 15, 1921.

UNITED STATES PATENT OFFICE.

HARRY P. DICKERSON, OF SALEM, OHIO.

HEEL-REMOVING DEVICE.

1,371,474.

Specification of Letters Patent. Patented Mar. 15, 1921.

Application filed May 26, 1920. Serial No. 384,504.

To all whom it may concern:

Be it known that I, HARRY P. DICKERSON, citizen of the United States, residing at Salem, in the county of Columbiana and 5 State of Ohio, have invented certain new and useful Improvements in Heel-Removing Devices, of which the following is a specification.

This invention pertains to new and useful improvements in heel removing devices.

The object of the invention is to provide a device for removing either portions or the entire heel of a shoe and to do so in most efficient and expeditious manner by the employment of novel instrumentalities.

Another object is to provide a heel clamp which readily adjusts itself to heels of different sizes and is automatic in operation, requiring no setting or readjusting by the 20 operator.

A still further object of the invention is to provide a removing element and operating parts so constructed that in operation the element first enters the heel and travels 25 horizontally through the same whereby the heel or portion thereof, is wedged apart; and then is expeditiously carried downward, whereby said element entirely removes said heel or portion from its support.

30 Among other objects of the invention is the provision of a device of the character described that will be strong and durable, and simple and comparatively inexpensive to construct, also one in which the several 35 parts will not be likely to get out of working order.

With the above and other objects in view the invention has relation to certain novel features of construction and operation, an 40 example of which is described in the following specification and illustrated in the accompanying drawings, wherein:

Figure 1 is a side elevation of the device showing the jaw open and ready to receive 45 the heel.

Fig. 2 is a side elevation of the upper end of the device showing the jaw as having completed its inward movement,

Fig. 3 is a similar view showing the jaw 50 at the end of its downward movement,

Fig. 4 is a horizontal sectional view taken on the line $a-a$ of Fig. 1,

Fig. 5 is a plan view of the head,

Fig. 6 is a sectional view of one of the 55 clamping members, and

Fig. 7 is a cross-sectional view on the line $x-x$ of Fig. 1.

In the drawings the numeral 1 designates a pedestal or vertical support having an enlarged base 2 and a shank 3 at its upper end. 60 The upper end of the shank is enlarged to form a head 4 which overhangs the shank and has a flat top. On the head a pair of clamping members 5 is pivotally mounted on screws 6 driven into the head and prevented from spreading by a connecting bar 7.

One of the members has a rounded boss 8 projecting into a correspondingly shaped recess 9 in the other member whereby a 70 hinge joint is formed between the members. Alined flanges 10 project upward along the rear edges of the said members and to the rear side of one of these members a flat spring 11 is secured so as to extend over the 75 other flange and engage in a keeper 12 carried by the latter. A stop pin 13 placed on the head is impinged by the spring when the clamping members are swung rearward during the clamping operation, whereby said 80 movement is limited. The spring returns the parts to normal position after each operation.

The clamping members have their forward edges curved as indicated at 14 and 85 also beveled as shown in Fig. 6. The curved edges of the members normally form an arcuate recess conforming to the general contour of the heel of a shoe. The shoe is placed upright with the back of the heel 90 in the recess of the clamping members as indicated in dotted lines in Fig. 2, so that the back of the heel is presented to the beveled edges 14 of said members, whereby said edges bite into the heel. 95

The heel is attacked by a swinging jaw or claw 15 pivoted on the upper end of a swinging support 16 pivoted at its lower end to an ear 17 projecting from the base 2. The upper end of the claw is curved 100 toward the head 3 and reduced to a substantial knife edge whereby a general wedge-shape is had. A hand lever 19 is pivoted at 21', the pivot 21' being some distance from the end of the lever. A pair of links 18 is pivoted to the lever by a bolt 20. The lever is bifurcated so as to straddle the shank as shown in Fig. 4, the links being on each side. The opposite end of the pair of links is secured on a pivot bolt 21 which 110

also pivots the claw on its support. In Fig. 1 the parts are shown ready to receive the shoe and as the lever 19 is swung down the claw is driven into the heel of the shoe so that the latter is wedged apart.

The inner end of the lever is curved toward the body of the lever as indicated at 22 and at its extremity is pivoted to a pair of links 23 which also straddle the shank 10 and have elongated slots 24 extending inward from their opposite ends. A headed bolt 25 fixed in the claw free from the support 16 projects through said slots. These slots permit the links 23 to be swung away 15 from the shank during the first movement of the claw or during the swinging of the same, but when the claw reaches the position shown in Fig. 2 the bolt 25 will be at the inner end of the slots and continued 20 movement of the lever will swing the claw on its pivot 21. This latter movement of the claw pulls the heel from the shoe and the claw moves down to the position shown in Fig. 3.

It will be noted that after reaching the end of the inward movement as shown in Fig. 2 the support 16 ceases to swing. This is due to the fact that the bifurcated end of the lever 19 is pivoted on the shank 3 so 30 as not to swing the links 18 after reaching this point. When the heel is forced into the clamping members the latter are swung toward each other on their pivots and not only clamp the heel but conform to the contour thereof so as to bite into the heel with a substantially uniform pressure at all points.

The heel is entirely removed below the line on which the claw enters and this is 40 of course controlled by the operator who places the shoe so as to remove only as much of the heel as is desired. It is pointed out that the counter and upper of the shoe are not brought into contact with any part 45 of the device and thus saved from injury or bruising. That portion of the heel which is removed is not injured and may be used again. In placing the heel for removal the forward edge of the claw and the top of 50 the clamping members being alined, little difficulty is experienced in adjusting the

shoe so that the parts will enter exactly between the same adjacent layers of the heel. It is preferable to position the device so that the operator may readily observe the 55 edges 14 of the clamping members and the front edge of the jaw.

The invention is presented as including all such modifications, changes and alterations as come within the scope of the appended claims.

What I claim, is:

1. In a heel removing device, a support, a fixed heel receiving member mounted on the support, and a heel removing member disposed so as to move toward the receiving member and constructed to be also moved downward with relation to said receiving member after completing its first movement.

2. In a heel removing device, a relatively fixed support, a heel receiving member mounted on the support, a swinging member, a lever, a connection between the lever and the swinging member for swinging the 75 said member and the heel entering member toward the heel receiving member, and means for moving the heel entering member downward after it has been swung.

3. In a heel removing device, a support, 80 a heel receiving member, a swinging member, a heel engaging element pivoted on the swinging member, a lever fulcrumed on the support, and connections between the lever and the said element constructed to swing 85 the member and the element simultaneously and then to hold the said member and move said element independently.

4. In a heel removing device, a support, a heel receiving member mounted on the 90 upper end of the support, a swinging member mounted adjacent the support, a claw pivoted on the upper end of the swinging member, a lever fulcrumed against the support, a pair of links extending between the 95 lever and the claw, and a second pair of links extending between the lever and the claw and pivoted to the latter through the agency of slots whereby said claw is swung after an initial movement of the claw.

In testimony whereof I affix my signature.

HARRY P. DICKERSON.
